UNITED STATES PATENT OFFICE.

DALLAS C. WOODWORTH, OF CHICAGO, ILLINOIS, ASSIGNOR TO CARL LAEMMLE, OF CHICAGO, ILLINOIS.

AUTOMATIC LIGHT-SHIELD FOR MOVING-PICTURE MACHINES.

No. 922,748.

Specification of Letters Patent.

Patented May 25, 1909.

Application filed January 30, 1909. Serial No. 475,249.

To all whom it may concern:

Be it known that I, DALLAS C. WOODWORTH, a citizen of the United States, residing at Chicago, county of Cook, and State of Illinois, have invented certain new and useful Improvements in Automatic Light-Shields for Moving-Picture Machines, of which the following is a specification.

My invention relates to moving picture machines, and more specifically to safety devices therefor.

The object of my invention is to provide a device of the character mentioned which will be in the nature of a shield so arranged as to 15 be adapted to be automatically actuated to intercept the light projected from the illuminating lamp of the machine, whenever the intermittently operated sprocket for any reason, while the machine is in operation, ceases 20 to draw the film or ribbon through the machine.

In moving picture machines, the rays of light are concentrated or focused at a point 25 adjacent to the film or ribbon, and inasmuch as the latter is usually composed of a highly inflammable and combustible material utmost care and caution is required to prevent the accidental ignition thereof. While the film is in motion it passes rapidly enough to 30 prevent undue heating, but if for any reason it stops, with the light concentrated thereon, the ignition thereof is inevitable.

It is a well known fact, particularly among 35 moving picture machine operators that the cause of the great majority of such accidents, that is the igniting of the picture films, is occasioned by the use of films containing torn or worn sprocket-holes, or thick splices. The films containing such sprocket-holes or 40 splices will invariably pass the feed sprocket of the machine, there being no tension of the film up to this point, the friction roller in engagement with the feed sprocket being itself adapted to effect the feeding thereof. How- 45 ever, the conditions at the intermittently operated sprocket are different. The film, in all machines in general use at the present time, before reaching the intermittently operated sprocket passes between tension 50 springs at the aperture of the machine, which press firmly against the same so as to hold it steady for known reasons. Now, when the thick splice or torn sprocket-holes in the film reach the intermittently operated sprocket,

the film clogs at that point, that is said 55 sprocket will cease to draw the same, owing to the restraining force of the tension springs which it or its friction roller is not powerful enough to overcome, hence causing the re- 60 tarding or stopping thereof at the point, with a result as before stated. It is therefore the object of my invention to provide, as before stated, a shield which will be adapted to be effectually actuated upon the occurrence of the circumstances above stated. 65

A still further object of my invention is to provide a device of the character mentioned which will be in the nature of an attachment adapted to be readily arranged upon a machine while in use or simultaneous with the manufacturing thereof. 70

A further object of the invention is to provide a shield device which will be highly efficient and which will be simple of construction, hence of low cost to manufacture. 75

Other objects will appear hereinafter.

With these objects in view my invention consists generally in a device characterized as above mentioned, the actuation of which will be effected by the enlargement of the 80 loop or slack ordinarily provided in the film just beyond the feed sprocket, such enlargement of said loop being obviously occasioned upon the occurrence of the circumstances just described. 85

My invention will be more readily understood by reference to the accompanying drawings forming a part of this specification, and in which,

Figure 1 is a side elevation of a moving 90 picture machine which is provided with the preferred form of my device, and Fig. 2 is a front elevation of the rear door or gate of the machine casing detached.

Referring now to the drawings 1 indicates 95 a moving picture machine casing, which may be of any ordinary or preferred form, and 2 the lens holder or tube thereof. Hingedly secured as at 3 by means of a hinge pin 4 to the rearward end of said casing is 100 the ordinary door or gate 5 thereof.

6 indicates the usual continuous feed sprocket of the machine which is so connected as to continuously feed the film or ribbon 105 when the machine is in operation.

8 is the usual friction roller mounted in a swinging frame 9, said roller being normally held in forced engagement with the sprocket

6, the edges of the film 7 resting, when the machine is in operation between said sprocket and said roller.

10 is the guide roller over which the film 5 passes before passing across the aperture 11 provided in the door 5 for the admission of the illuminating light from the machine lamp (not shown). Between said sprocket 6 and roller 10 the film is looped at 12 for 10 known reasons. Provided upon said door 5 ordinarily, are elongated tensional leaf springs (not shown) between which and the inside surface of the door the film passes, such being provided to facilitate holding the 15 latter steady or rigid while projecting light therethrough. After leaving the tension springs the film passes between the ordinary intermittently operated sprocket 13 and the friction roller 13', thence to a reel (not 20 shown) upon which it is coiled. Thus far my description has dealt only with the general construction and operation of a moving picture machine, no claim whatsoever being laid to the same.

25 What I am about to claim as novel will be described in the following: Arranged upon the outer surface of the door 5, the same being secured thereto in any suitable manner, but preferably by means of brackets 14 secured as by screws 15 to said door, is a preferably rectangular plate 16 formed of any suitable material but preferably of sheet aluminum arranged parallel to said door 5. Said plate 16 is so arranged upon said door 30 that an aperture 17 provided therein which is of dimensions substantially the same as those of the door aperture 11, will be in direct alignment with the latter, as clearly shown in Fig. 2. Having its shank 18 swingingly mounted upon a pivotal pin 19 secured in and projecting from the outer surface of said plate 16 is a plate or shield proper 20, the same being of such a shape and so arranged as to be adapted, when abutting a 40 stop 21 projecting from the plate 16, to entirely cover the aperture 17 as clearly shown in dotted lines in Fig. 2. A coil spring 22 the respective extremities of which are secured to said pin 19 and said shank 18, is 45 adapted to normally hold said shield 20 in closing position.

Having its lower edge 23 hingedly secured to the upper edge of the plate 16 is a curved plate or trigger 24, said plate being so positioned and arranged as to be adapted to be 50 engaged and rocked by the film loop 12 upon the enlargement thereof. Depending from the lower edge of said plate 24 is an angular arm 25 the extremity 26 of which extends 55 through a slot 27 provided in the plate 16 for the reception of the same. Said extremity 26 of said arm 25 is adapted to act in the capacity of a stop for the shield shank 18, the same being adapted when in engagement 60 with the edge 28 thereof, to hold said shield

in opened position, as clearly shown in full lines in Fig. 2. A coil spring 29 the respective extremities of which are in engagement with said trigger plate 24 and the upper edge of said base plate 16, is adapted normally to 70 hold said arm extremity 26 in engagement with said shield shank.

In the operation of the machine the shield blade 20 is arranged in open position as shown in full lines. Now, upon the occurrence of the before described circumstances, that is of the intermittently operated sprocket 13 ceasing to draw the film through the machine as it is fed by the feeding sprocket 6, the film loop 12 will immediately 80 enlarge. Upon such enlargement of said loop said film will obviously contact the inside surface of the trigger plate 24 forcing the same over, thereby causing the withdrawal of the extremity 26 thereof from engagement with the shield shank 18, the shield 20 in such event being immediately rocked into closing position, thereby intercepting the projected rays of light and hence 85 obviously obviating all possibility of the ignition of the film. In order that the shield 20 may be readily returned to initial position, the edge portion 30 of the shank thereof is bent outwardly as shown, such provision obviously eliminating the necessity of 90 the machine operator having to depress the trigger extremity 26 in returning the shield to its initial position.

While I have shown what I deem to be the preferable form of my device, I do not wish 100 to be limited thereto, as there might be many changes made in the details of construction and arrangement of parts without departing from the spirit of my invention. And although I have shown my device arranged upon a machine of particular design, 105 I may use the same upon any other machine to which it is applicable.

Having described my invention what I claim as new and desire to secure by Letters 110 Patent is:

1. In a device of the class described, the combination with a moving picture machine, of a normally withdrawn shield adapted to be interposed between the illuminating 115 source and the light aperture provided in said machine casing, and means in operative connection with said shield and in the path of an enlargement of the film loop whereby said shield will be released, substantially 120 as described.

2. In a device of the class described, the combination with a moving picture machine, of a normally withdrawn shield adapted to be interposed between the picture film and 125 the illuminating source, said shield being adapted when released to intercept the light rays projected from said illuminating source, and means in operative connection with said shield and in the path of an enlargement of

the film loop, whereby said shield will be released, substantially as described.

3. In a device of the class described, the combination with a moving picture machine, 5 of a swingingly mounted normally withdrawn shield adapted to be interposed between the picture film and the illuminating source, said shield being adapted when released to swing into a position intercepting the light rays projected from said illuminating source, and means in operative connection with said shield and in the path of an enlargement of the film loop, whereby 10 said shield will be released, substantially as described.

4. In a device of the class described, the combination with a moving picture machine, of a swingingly mounted normally withdrawn shield interposed between the picture film 20 and the illuminating source, said shield being adapted when released to intercept the light rays projected from said illuminating source, and means adapted to hold said shield in a position out of the path of said 25 light rays, said means being adapted, upon the enlargement of the film loop, to release said shield, substantially as described.

5. In a device of the class described, the combination with a moving picture machine, 30 of a swingingly mounted normally withdrawn shield interposed between the picture film and the illuminating source, said shield being adapted when released to intercept the light rays projected from said illuminating 35 source, a plate arranged in the path of the film loop when enlarged, a portion of said plate being adapted to hold said shield in a position out of the path of said light rays, said plate being adapted, upon the enlargement 40 of the film loop, to release said shield, substantially as described.

6. In a device of the class described, the combination with a moving picture machine,

of a swingingly mounted normally withdrawn shield interposed between the light aperture 45 therein and an illuminating source, said shield being adapted when released to intercept the light rays projected from said illuminating source, a hingedly mounted plate, the upper end portion of said plate 50 being positioned in the path of the film loop when enlarged, the lower portion of said plate being adapted to hold said shield in a position out of the path of said light rays, said plate being adapted when contacted 55 by said enlarging film loop, to release said shield, substantially as described.

7. In a device of the class described, the combination with a moving picture machine and the casing thereof, of an apertured base 60 plate mounted parallel with the rearward end portion of the machine casing, the aperture in said plate being in alignment with the light aperture in said machine casing, a normally withdrawn shield swingingly mounted upon said plate adapted when released to intercept the light rays projected from the illuminating source, and a curved trigger plate hingedly secured to the upper edge of said base plate, the upper end portion 70 of said plate being positioned in the path of the picture film loop when enlarging, the lower end portion of said plate being adapted normally to hold said shield in a position out of the path of said light rays, said plate 75 being adapted when contacted by the enlarging film loop to release said shield, substantially as described.

In testimony whereof I have signed my name to this specification in the presence of 80 two subscribing witnesses.

DALLAS C. WOODWORTH.
